UNITED STATES PATENT OFFICE.

GUSTAVE E. PETERSON, OF HARTFORD, CONNECTICUT.

INDICATOR FOR LATHES.

No. 811,244.

Specification of Letters Patent.

Patented Jan. 30, 1906.

Application filed April 20, 1904. Serial No. 203,984.

To all whom it may concern:

Be it known that I, GUSTAVE E. PETERSON, a citizen of the United States, and a resident of Hartford, in the county of Hartford and State of Connecticut, have invented a new and Improved Indicator for Lathes, of which the following is a specification.

My invention relates to the class of devices used for determining whether a piece of work is accurately located in a lathe or planer, and if not to what extent such piece of work may be out of its true position, and the object of my invention is to provide a device of this class that may be readily applied to work of various shapes and forms and that, in fact, may accommodate itself to work of any shape or form and in any position; and a further object is to provide a device of this class in which variations in the location of the work from a true position may be plainly indicated to a nicety. A form of device in the use of which these objects may be attained is illustrated in the accompanying drawings, in which—

Figure 1 is a view of a portion of a lathe, showing a device embodying my invention applied thereto. Fig. 2 is a view, on enlarged scale, of my improved indicator, showing its application to one form of work. Fig. 3 is an edge view of the indicator. Fig. 4 is a detail view of the indicating-lever. Fig. 5 is a top view of the indicator, showing another method of applying it to a piece of work.

In the accompanying drawings the numeral 1 indicates the bed of a lathe, on which the carrier 2 is mounted and bearing the tool-post 3. This tool-post is mounted in the usual manner appurtenant to the chuck 4, in which a piece of work 5 is secured and in connection with which my improved indicator is used, the indicator being clamped and held in the tool-post in the same manner as a tool for operating upon the piece of work held in the chuck.

My improved indicator includes a base 6, suitably shaped to be secured in the tool-post of the lathe, as above described, and an indicator-arm 7, pivotally connected or attached to said base, as by means of a link 8. This link is pivoted to the base 6 by a pivot 9, which allows the indicator-arm 7 to be swung in a plane in one direction, and the link is connected or secured to the indicator-arm

by the pivot 10, which allows the indicator-arm to be swung in a plane in a transverse direction, this method of connecting the indicator-arm with the base forming a connection having a plural number of pivots with clamping means.

An indicating pointer or hand 11 is pivotally mounted on the indicator-arm 7, the free end of said pointer operating in connection with graduations placed upon the arm. The pointer is preferably mounted on a pivot supported by the bracket 12 on the arm and bears at the end opposite to that located appurtenant to the graduations a stud 13. This stud 13 is located between spring-arms 14 on the under side of the indicating-lever 15. This construction provides a resilient or yielding connection between the indexing-lever and the pointer and insures a tight pivotal connection, free from lost motion. It will of course be understood that the spring-arms 14 are sufficiently rigid to maintain a tight connection with the stud 13 under the comparatively easy movement of the pointer and take up any wear between the parts. This indicating-lever is mounted on a pivot 16, borne by the arm 7, and has three working faces *a*, *b*, and *c*. A spring 17 is also secured to the under side of the indicating-lever, the free end of the spring being in engagement with a toothed disk 18. This toothed disk has a recess 19, in which said spring engages, and a pawl 20, secured on the indicator-arm 7, engages with the teeth on the periphery of the disk to hold it from accidental movement. From this construction it will be seen that the free end of the spring 17 may be so located with reference to the end secured to the indicating-lever that it may be shifted to either one side or the other of a line passing through the pivots of the pointer and lever. Thus the pointer will be effected in various ways dependent upon the tensioning of the spring either at one side or the other of the line connecting the two pivotal points. With the spring exerting force, as indicated in Fig. 2, the working faces *b* and *c* may be made use of. By shifting the end of the spring to the position indicated in Fig. 5 the working face *a* becomes operative.

It will be noted that the indicating-finger 11 and the indicating-lever 15 are each provided with a short and long arm. The short

arm of the lever 15 is provided with the working surfaces *a*, *b*, and *c*, and the long arm is in engagement with the short arm of the indicating-pointer, so that a comparatively great amount of movement will be imparted to the free end of the pointer 11 from a very small amount of movement of the short arm of the lever 15, caused by any irregularity or untrueness of the work 5 in contact with either 10 of the working faces *a*, *b*, or *c* of said lever.

As shown in Fig. 1 of the drawings, the working face *c* is in engagement behind a shoulder within a recess in a piece of work, and in Fig. 2 the face *b* is shown in engagement with the inner surface of a piece of work held in the chuck, while in Fig. 5 I have shown the face *a* in engagement with the bottom of a recess in a piece of work. It will be seen that by providing the three working 20 faces in connection with the improved construction of joint by which the arm 7 is connected to the base 6 the latter may be clamped in the tool-post of a lathe and the working faces may be located to engage any part of a 25 piece of work held in the chuck 4 to indicate any untrueness of said piece of work.

In the operation of the device the base 6 is clamped in the tool-post and one of the faces *a*, *b*, or *c* is brought into engagement with the 30 work to be tested and the arm 7 is swung or the base 6 moved until the pointer 11 is located opposite the zero-mark on the index. The piece of work 5 then being rotated or moved, the degree of imperfection in said 35 piece of work can be readily ascertained. The movement of the free end of the pointer the distance of one space denoted by the marks on the index indicates a movement of the piece of work the one-thousandth part of an 40 inch.

Obviously the improved connection between the base and indicator-arm plays an important part in the adjustment of the indicator-arm and pointer. The arm may be 45 nicely centered with reference to the work through one of the joints, and then by means of the other joint the arm may be moved to insure the positioning of the pointer at the zero-mark. It may be observed that the 50 scale underlying the pointer reads in either direction, and the simple shifting of the spring 17 to make either of the working faces *a*, *b*, or *c* effective determines which side of the scale 55 the pointer will traverse under the influence of the spring.

What I claim as my invention, and desire to secure by Letters Patent, is—

1. In an indicating device, an indicator-arm with means of attachment, an indicating-lever mounted on said arm and including 60 a portion extending lengthwise of the arm and an offset portion located transverse to the arm and bearing a plural number of con-

tact-faces, an indicating-pointer located on the arm in extension and connected with the 65 main part of said lever, and means for resiliently holding the lever and pointer in normal position.

2. In an indicator, a base, a link pivoted to the base, a clamp for said pivot, an indicator-arm pivoted to said link by a pivot extending transverse to the pivot between the link and base, means for clamping the pivot 70 between the arm and link, an indicating-lever mounted on said arm and having a main portion extending lengthwise of the arm and a bent portion extending transverse to the main portion said bent portion having a plural number of contact-faces, a pointer located on the arm in extension of and connected 75 with the main part of the lever, and means for resiliently holding the arm and pointer in normal position.

3. In an indicating device, an indicator-arm with means of attachment, an indicating-lever extending lengthwise of the arm and pivoted thereon and having a short extension located at an angle to the main portion 85 of the lever, said short extension having contact-points arranged laterally on opposite 90 sides of the lengthwise center thereof, and an indicating-pointer to be operated by said lever.

4. In an indicating device, a narrow indicator-arm with means of attachment, an indicating-lever pivoted on the arm with a 95 short extension located at an angle of less than ninety degrees to the main portion of the lever, said short extension forming a contact and the longer extension from the 100 pivot connected with an indicating-pointer, the indicating-pointer pivoted on the arm with a short extension from the pivot connected with the indicating-lever and with a longer extension from the pivot forming an 105 indicating-pointer, and means for resiliently holding the pointer and lever in normal position.

5. In an indicating device an indicator-arm with means for attachment, an indicating-lever mounted on the arm and having an extension provided with a plural number of contact-faces, a pair of spring-arms secured on the under side of the lever, an indicating-pointer having a short arm with a stud located 115 between the resilient arms on the lever, the opposite end of the pointer forming an indicating device and means for resiliently holding the pointer and lever in normal position.

6. In an indicator, an indicator-arm provided with means for attachment to a tool-post, an indicating-lever pivotally connected to the arm, a pointer mounted on the arm, a connection between said pointer and lever including a pair of resilient members mounted 125 on one of said parts, and a stud projecting

from the opposite part and arranged between said resilient members.

7. In an indicator, an arm provided with means of attachment to a tool-post, an indicating-pointer pivotally mounted on the arm, an indicating-lever pivotally mounted on the arm and connected with the pointer, a spring with one end engaged with the arm, a disk

having a recess for engagement of the opposite end of said spring, and means for holding the disk against accidental movement.
